CLOTHESLINE COVERING DEVICE

Julius Tarlazzi, North Bergen, N. J.

Application September 15, 1938, Serial No. 230,061

7 Claims. (Cl. 211—119)

This invention relates to improvements in clothes line covering devices and more particularly to such a device in which the clothes line covering is wound and unwound automatically upon movement of the clothes line.

Such devices in the past have been complicated in construction. Furthermore the reel containing the covering tape in such a device, was not easily detachable from the same so that 10 said reel might be removed and brought indoors where the tape might be kept protected and clean.

An object of my invention is to provide a clothes line covering device in which the line 15 covering is automatically wound and unwound upon movement of the clothes line and the clothes line covered so that clothes hanged upon the same will not become soiled.

Another object of my invention is to provide 20 a clothes line covering device in which the tape containing reel may be easily detachable from the remainder of the device in order that the clothes line covering may be removed from the remainder of the device and it is not necessary 25 to leave the same out of doors with the device when not in use and the same may thereby be kept clean.

A further object of my invention is to provide 30 means for insuring an even feeding of the clothes line covering tape when the same is being unwound from the reel containing the same.

Other objects will appear or will be obvious 35 from a consideration of the detailed description which follows when taken in conjunction with the accompanying drawing.

The device of the present invention consists 40 of a frame in which is mounted two pulleys, one beneath the other, over which a clothes line passes, the flanges of the lowermost pulley being serrated about their circumference. Pivottally 45 mounted on the frame is a reel holding member in which is rotatably and detachably mounted a reel containing the clothes line covering tape, said reel holding member being acted upon by 50 a spring so that the tape on the reel may be held in contact with the serrated edges of the lowermost clothes line pulley in order that longitudinal movement of the clothes line will either wind or unwind the clothes line covering tape 55 from the reel. A braking device is mounted on said reel holding member to frictionally engage the side of the flange of the tape holding reel in order that the tape will be unwound from the reel evenly. A tape guiding means is mounted 60 on said reel holding member to guide the tape

as the same is being wound or unwound from the reel.

It will be understood, however, that the invention is not restricted to the exact disclosure, but is susceptible to such changes and modifications 5 which are within the scope of the appended claims.

Referring to the accompanying drawing:

Figure 1 is a side elevational view of the device of the present invention.

Figure 2 is a view taken on the line 2—2 of Figure 1.

Figure 3 is a perspective view showing the clothes line covering tape fastened to the clothes line.

Figure 4 is a view showing the manner of 15 mounting the covering tape reel on the reel holding member.

Like numerals refer to like parts throughout 20 the several views.

The pulley holding frame 10 has extension 25 arms 11 adapted to engage a hook 12 or other fastening means so that said frame may be attached to a wall 13. Rotatably mounted in the frame 10 are pulleys 14 and 15, the pulley 15 being mounted below the pulley 14 and preferably being of a larger diameter.

The flanges of the pulley 15 are serrated about 30 their circumference as shown at 16.

An endless clothes line 17 passes about the 35 pulleys 14 and 15 and about pulleys, not shown, which are mounted on a wall or similar support opposite the frame 10 and wall 13.

Pivottally mounted on the frame 10 at 17a is a 40 reel supporting bracket 18 containing an enlarged portion 19 which is slotted at 20 to accommodate the axle 21 of a clothes line covering tape reel 22 so that said axle may rotate in the member 18 and the reel 22 removed therefrom through the slot 20. A clothes line covering tape 22a is wound on the reel 22. A lock plate 45 23 is pivottally mounted on the enlarged portion 19 of the member 18 so that the tape reel may be locked in position in the slot 20.

The bracket 18 has an extension 24 on which 50 is pivottally mounted a brake 25, having a rubber surface 26 adapted to frictionally engage the flange of the tape reel 22. The side 27 of the brake 25 is tapered away from the flange of the reel 22 so that when the tape 22a is being wound 55 onto the reel 22 the frictional engagement of the rubber surface 26 with the flange of the tape reel will release the brake 25 so that it will engage the flange only lightly.

When the tape is being unwound from the reel, 60

the frictional engagement of the rubber surface 26 will rotate the brake about the pivot increasing the pressure of the rubber surface against the flange which will not allow the tape to be 5 unwound too quickly.

A tape guide 28 having fingers 29 and 30 is mounted on the front of the bracket 18. The tape guide has a slot 31 formed therein through which the tape 22a passes. The fingers 29 and 10 30 prevent the edges of the tape from folding over and insures the tape being wound onto the reel flatly.

A spring 32, mounted at 17, acts on the bracket 18 pressing the tape 22a into contact with the 15 serrated circumference of the flanges of the pulley 15. Since the pulley 15 is of a lesser width than the tape reel 22, the flanges of the pulley 15 bear directly against the tape 22a so that rotation of the pulley 15 by movement of the clothes line 17 will rotate the reel 22 by action 20 of the serrated flanges on the tape, either winding or unwinding the tape depending on the direction of rotation.

A tip 33, preferably of light metal, having 25 prongs 34 and 35 is fastened to the end of the tape 22a. The prongs 34 and 35 may be pressed into the clothes line 17 and the tape thereby fastened to said line.

In the operation of the device, the pulley holding frame 10 is fastened to any desired support such as a hook 12 on a wall 13, usually out of doors. An endless clothes line 17 passes over the pulleys 14 and 15 rotatably mounted in the frame 10 and over a pulley, not shown in the drawing, rotatably mounted on a support opposite to the wall 13.

The tape reel 22 containing the clothes line covering tape 22a is placed in the bracket 18 by moving the bracket 18 outwardly away from the pulley holding frame 10, against the tension of the spring 32 since the spring 32 presses the bracket 18 against the frame when the reel 22 is not mounted thereon, and placing the axle 21 of the reel 22 in the slot 20. The reel is then locked in place by moving the lock plate 23 so that the slot therein engages the axle 21 the free end of said plate being snapped over the bracket 18 locking the reel 22 in the bracket 18.

The tape 22a, wound on the reel 22, is held firmly against the serrated edges of the flanges on the pulley 15 by action of the spring 32 on the bracket 18 so that rotation of the pulley 15 will rotate the reel 22.

The tip 33, fastened to the end of the tape 22a 55 is then placed through the slot in the tape guide 28 and fastened to the lower lead of the clothes line 17 by pressing the prongs 34 and 35 into the line.

When it is desired to hang clothes on the line, 60 the clothes line is moved longitudinally in the direction of the arrow in Figure 1. This movement will rotate the pulleys 14 and 15 in an anti-clockwise direction and the engagement of the serrated edges on the circumference of the flanges of the pulley 15 with the tape 22a will 65 rotate the reel 22 in a clockwise direction unwinding the tape from the reel as the clothes line moves in the direction indicated in the drawing.

When enough covering tape is fed out from 70 the reel 22 to cover the amount of line required by a piece of washing, the piece of washing is placed over the tape 22a, the tape 22a coming in contact with the cloth line 17, the article of washing being held away from contacting the

line by means of the tape thereby preventing the soiling of the washing. The clothes pins which hold the piece of washing in position, also hold the tape in position on the line. The line is then moved forward in the direction of the arrow in Figure 1 so that another article may be placed thereon.

As the tape is unwound from the reel 22 and the diameter of the spool of tape on the reel becomes less, the tape remaining on the reel is 10 pressed into engagement with the serrated circumference of the flanges of the pulley 15 by the action of the spring 32 on the bracket 18 pivoted to the frame 10 at 17a.

The rubber surface 26 of the brake 25 in its 15 normal position lightly engages the flange of the reel 22 frictionally. As the reel 22 moves in an anti-clockwise direction feeding out the tape 22a, the friction between the surface 26 and the flange is increased due to the taper on the braking surface. This prevents too much tape from being unwound from the reel when the clothes line is jerked forward since the reel is held from spinning.

When it is desired to remove the washing from 25 the clothes line, the line 17 is moved in a direction opposite to that indicated by the arrow in Figure 1. This moves the pulleys 14 and 15 in a clockwise direction, the reel 22 moving in an anti-clockwise direction through the engagement of 30 the tape 22a thereon with the serrated flanges on the pulley 15, thereby winding the tape 22a onto the reel 22.

As the tape is wound onto the reel 22 and the diameter of the spool of tape on the reel becomes 35 larger, the center of the reel 22 moves away from the pulley 15, the tape on the reel, however, always being pressed into engagement with the serrated edges 16 on the flanges of the pulley 15 by action of the spring 32 on the bracket 18 on which the reel 22 is mounted.

The brake 25 is released during the winding of the tape onto the reel 22, the tapered surface 27 of the brake engaging the flange of the reel 22.

When all of the washing has been removed 45 from the line and the tape 22a is fully wound on the reel 22, the reel may be removed from the bracket 18 by swinging the lock plate 23 out of engagement with the bracket 18 and axle 21, as shown in Figure 4 of the drawing. The axle is then slid from the slot 20 in the enlarged portion 19 of the bracket 18 and the reel 22 thereby removed from the device.

The bracket 18 is moved by the spring 32 until the arms of the bracket rest against the frame 10.

The reel of tape may then be stored in a suitable place where the same may be kept clean until it is again desired to use the same. The clothes line, and the remainder of the device may be left hanging out of doors, since any dust, dirt or soot falling on the line will be covered by the tape 22a when the line is used which tape will be kept clean between uses.

It may be readily understood that the present invention may be adapted in different ways to 65 accomplish the purposes set forth and it is not my intention to limit the invention to the exact details of construction shown and described but rather to cover all equivalent structures as defined by the scope of the following claims.

I claim:

1. In a line covering device, a frame, pulleys rotatably mounted one above the other in said frame over which an endless line passes to provide upper and lower leads, a bracket pivotally 75

mounted on said frame, a reel of tape rotatably mounted in said bracket adapted to frictionally engage the circumference of the flanges of the lower pulley whereby rotation of the pulley by movement of the line in one direction will wind the tape upon said reel and rotation of the pulley in the opposite direction will unwind said tape from the reel, tape guiding means mounted on said bracket through which said tape is passed and means for fastening said tape to the lower lead of said line, said line being covered with tape by movement of the same in a direction to unwind said tape from said reel and uncovered by movement of the line in a direction to wind said tape on said reel.

2. In a line covering device, a frame, pulleys rotatably mounted one above the other in said frame over which an endless line passes to provide upper and lower leads, the circumference of the flanges of said lower pulley being serrated, a bracket pivotally mounted on said frame, a reel of tape rotatably mounted in said bracket adapted to frictionally engage the circumference of the flanges of the lower pulley whereby rotation of the pulley by movement of the line in one direction will wind the tape upon said reel and rotation of the pulley in the opposite direction will unwind said tape from the reel, a spring mounted on said frame and said bracket adapted to hold said tape in frictional engagement with said flanges, tape guiding means mounted on said bracket through which said tape is passed, and means for fastening said tape to the lower lead of said line, said line being covered with tape by movement of the same in a direction to unwind said tape from said reel and uncovered by movement of the line in a direction to wind said tape on said reel.

3. In a line covering device, a frame, pulleys rotatably mounted one above the other in said frame over which an endless line passes to provide upper and lower leads, a bracket pivotally mounted on said frame, a reel of tape rotatably mounted in said bracket adapted to frictionally engage the circumference of the flanges of the lower pulley whereby rotation of the pulley by movement of the line in one direction will wind the tape upon said reel and rotation of the pulley in the opposite direction will unwind said tape from the reel, braking means adapted to automatically frictionally act upon the flange of said reel when the tape is being unwound from the same and released when said tape is being wound upon said reel, a spring mounted on said frame and said bracket adapted to hold said tape in frictional engagement with said flanges, tape guiding means mounted on said bracket through which said tape is passed, and means for fastening said tape to the lower lead of said line, said line being covered with tape by movement of the same in a direction to unwind said tape from said reel and uncovered by movement of the line in a direction to wind said tape onto the said reel.

4. In a line covering device, a frame, pulleys rotatably mounted one above the other in said frame over which an endless line passes to provide upper and lower leads, the circumference of the flanges of said lower pulley being serrated, a bracket pivotally mounted on said frame, an enlarged bearing portion on said bracket having a slot therein, a reel of tape removably and rotatably mounted in said slot adapted to frictionally engage the circumference of the flanges of the lower pulley whereby rotation of the pulley by

ley by movement of the line in one direction will wind the tape upon said reel and rotation of the pulley in the opposite direction will unwind said tape from the reel, a spring mounted on said frame and said bracket adapted to hold said tape in frictional engagement with said flanges, tape guiding means mounted on said bracket through which said tape is passed, and means for fastening said tape to the lower lead of said line, said line being covered with tape by movement of the same in a direction to unwind said tape from said reel and uncovered by movement of the line in a direction to wind said tape on said reel.

5. In a line covering device, a frame, pulleys rotatably mounted one above the other in said frame over which an endless line passes to provide upper and lower leads, the circumference of the flanges of said lower pulley being serrated, a bracket pivotally mounted on said frame, an enlarged bearing portion on said bracket having a slot therein, a reel of tape removably and rotatably mounted in said slot adapted to frictionally engage the circumference of the flanges of the lower pulley whereby rotation of the pulley by movement of the line in one direction will wind the tape upon said reel and rotation of the pulley in the opposite direction will unwind said tape from the reel, braking means adapted to automatically frictionally act upon the flange of said reel when the tape is being unwound from the same and released when said tape is being wound upon said reel, a spring mounted on said frame and said bracket adapted to hold said tape in frictional engagement with said flanges, tape guiding means mounted on said bracket through which said tape is passed, and means for fastening said tape to the lower lead of said line, said line being covered with tape by movement of the same in a direction to unwind said tape from said reel and uncovered by movement of the line in a direction to wind said tape on said reel.

6. In a line covering device, a frame, pulleys rotatably mounted one above the other in said frame over which an endless line passes to provide upper and lower leads, the circumference of the flanges of said lower pulley being serrated, a bracket pivotally mounted on said frame, an enlarged bearing portion on said bracket having a slot therein, a reel of tape removably and rotatably mounted in said slot adapted to frictionally engage the circumference of the flanges of the lower pulley whereby rotation of the pulley by movement of the line in one direction will wind the tape upon said reel and rotation of the pulley in the opposite direction will unwind said tape from the reel, locking means adapted to lock said reel in said slot, a spring mounted on said frame and said bracket adapted to hold said tape in frictional engagement with said flanges, tape guiding means mounted on said bracket through which said tape is passed, and means for fastening said tape to the lower lead of said line, said line being covered with tape by movement of the same in a direction to unwind said tape from said reel and uncovered by movement of the line in a direction to wind said tape on said reel.

7. In a line covering device, a frame, pulleys rotatably mounted one above the other in said frame over which an endless line passes to provide upper and lower leads, the circumference of the flanges of said lower pulley being serrated, a bracket pivotally mounted on said frame, an enlarged bearing portion on said bracket having a

slot therein, a reel of tape removably and rotatably mounted in said slot adapted to frictionally engage the circumference of the flanges of the lower pulley whereby rotation of the pulley by movement of the line in one direction will wind the tape upon said reel and rotation of the pulley in the opposite direction will unwind said tape from the reel, braking means adapted to automatically frictionally act upon the flange of said reel when the tape is being unwound from the same and released when said tape is being wound upon said reel, locking means adapted to lock

said reel in said slot, a spring mounted on said frame and said bracket adapted to hold said tape, in frictional engagement with said flanges, tape guiding means mounted on said bracket through which said tape is passed, and means for fastening said tape to the lower lead of said line, said line being covered with tape by movement of the same in a direction to unwind said tape from said reel and uncovered by movement of the line in a direction to wind said tape on said reel.

JULIUS TARLAZZI.
